(57) CLAIM

I claim the ornamental design for a bikini brassiere, as shown and described.

DESCRIPTION

FIG. 1 is a front view of a bikini brassiere showing my new design; and,

FIG. 2 is a rear view thereof.

The broken lines in FIGS. 1 and 2 represent the portions of the bikini brassiere, which form no part of the claimed design.

1 Claim, 2 Drawing Sheets
